DESIGN FOR A SPORT SHIRT

Fred E. Newman, Chicago, Ill.

Application August 3, 1936, Serial No. 64,203

Term of patent 14 years

To all whom it may concern:

Be it known that I, Fred E. Newman, a citizen of the United States, residing at Chicago, Cook County, Illinois, have invented a new, original, and ornamental Design for a Sport Shirt, of which the following is a specification, reference being had to the accompanying drawing forming a part hereof, which is a front perspective view of a sport shirt showing my new design. The back of the shirt is conventional.

The characteristic feature of my design resides in the applique of contrasting color of the configuration shown on the front of the shirt, as shown.

I claim:

The ornamental design for a sport shirt, as shown and described.

FRED E. NEWMAN.
